UNITED STATES PATENT OFFICE.

HARRY C. GAMMETER, OF CLEVELAND HEIGHTS, OHIO, ASSIGNOR TO THE AMERICAN MULTIGRAPH COMPANY, OF CLEVELAND, OHIO, A CORPORATION OF OHIO.

MECHANISM FOR FEEDING TAGS, CARDS, ETC.

Application filed October 6, 1920. Serial No. 415,153.

To all whom it may concern:

Be it known that I, HARRY C. GAMMETER, residing at Cleveland Heights, in the county of Cuyahoga and State of Ohio, have invented a certain new and useful Improvement in Mechanism for Feeding Tags, Cards, Etc., of which the following is a full, clear, and exact description, reference being had to the accompanying drawings.

This invention relates to mechanism for feeding a continuous strip of paper to a rotary printing machine, the object being to provide accuracy in the presentation of certain regions of the strip to the impressing device on the printing machine. In printing tags for instance, it is desirable in the interest of economy to print them as a connected strip, the tags being separated after printing. In such work, however, it is very important that the different regions be successively re-registered with the printing mechanism, because with an ordinary feeding mechanism errors in registration accumulate with successive impressions, and thus even a slight lack of registration becomes so great in a number of impressions as to render the product useless, for instance, where a single imprint comes on two tags.

It is a specific object of this invention to provide means whereby a continuous paper strip is fed to a rotary printing machine, and is registered therewith for each impression, thus preventing accumulation of the slight errors in presentation.

My invention is well adapted for printing such price-tags as are attached to garments, the blank for these tags consisting of a continuous strip notched at the edges to identify the four corners of the tag. My mechanism uses these notches as a factor in registering each tag with the printing form. The tag strip is fed forward for each impression a distance slightly greater than the height of one tag, and then is drawn back until the positioning mechanism engages the corner notches, and thus holds the strip with the tag accurately presented.

A further feature of my invention is an arrangement of retracting rollers and positioning fingers in such form that they may be conveniently employed in conjunction with a multigraph, which has rollers for advancing the paper to the impression line.

A further feature of my invention is an arrangement of all of the aforesaid mecha-

nism in such a manner that it may be adjusted laterally and longitudinally to feed and register various widths and lengths of tag.

The above and other features of the invention are hereinafter more fully explained, and the essential characteristics are set out in the claims.

In the drawings, Fig. 1 is an end view partly in section of a Gammeter printing machine showing my invention applied thereto; Fig. 2 is a detail partly in section showing means for feeding the material; Fig. 3 is an elevation partly in section showing means for aligning the material; Fig. 4 is an end view of the parts shown in Fig. 3; Fig. 5 is a top plan view of the parts shown in Fig. 3; Fig. 6 is a view similar to Fig. 4 showing the levers which engage the material; Fig. 7 is a fragmentary view of the base plate showing the levers and guide means; Fig. 8 is an end view of the aligning roller showing the pawl and ratchet and Fig. 9 shows a strip of material adapted to be used with my invention.

Referring to the drawings by reference characters 5 represents a base member and 6 a portion of the supporting frame. The rotary printing drum 7 is journaled on an axle 8 in the frame and may be provided with a handle by means of which it can be rotated. The printing drum may have rails (a few of which are shown at 10 in Fig. 1) for carrying type, or other printing surface may be employed and carried in any manner desired. This is all well known and, therefore, is not shown in detail. A pair of spools shown at 12 carry the impression ribbon from which the printing is done. The impression member shown at 14 is journaled on the shaft 15, suitable gearing being provided whereby the drum and impression member may rotate in unison and paper fed to the co-operating surfaces of the drum and impression member will be drawn in between them and printed. To provide a proper feed for the material being printed the following mechanism may be used.

A roller 18 is continually driven thru the platen gear or other means (not shown). Above this roller is a second roller 19 which may be shiftably carried by the arm 20 of a bell crank lever 21. This bell crank lever 21 may be pivoted at 22 to a suitable portion of the frame. The other arm 24 of the bell

crank may be provided with a roller 25 adapted to ride over a rib 26 shown as located on the periphery of the drum. The bell crank lever arm 24 may be urged upward into engagement with the drum by means of a spring (not shown) carried on the pivoted member. This causes the roller 25 to normally be in engagement with the periphery of the drum and thereby normally maintains the roller 19 free of engagement with the roller 18.

During an interval in each revolution of the drum the rib 26 depresses the bell crank as shown in Fig. 2 and during this interval causes the rollers 19 and 20 to grip the paper or other material between them and thereby advance the paper an amount dependent on the length of the rib 26. In order that the paper may be accurately aligned with regard to the printing type the following mechanism may be employed.

A table member 32 is provided with a turned down edge 33 which removably engages a groove 34 in the base 5 and may also be provided with an angle member 310 adapted to removably engage a link 341, the latter being supported at 342 on a portion of the base shown at 343. A suitable plate member shown at 42 may be removably secured by thumb screws 43 to the member 32 and on this plate the aligning mechanism may be supported. A freely rotatable roller shown at 30 may be journaled in the block 31 which is indicated as attached to the table member 32. A second roller 35 is shown as journaled at 351 in a bearing block 36, which is indicated as removably secured by screws 37 to a leaf spring 38. The leaf spring may in turn be removably secured by the fastening 40 to a block 41.

The block 41 is shown as removably secured to a plate 42 by a screw 45 and a bolt 46 secured by a nut 47. The spring 38 is shown as extending parallel to the plate 42. In order that the tension of this spring may be adjusted and thereby the pressure which the roll 35 exerts on the roll 30 may be regulated I may provide means shown here as comprising a thumb screw 43 threaded onto the upper part of the bolt 46. By turning the thumb screw the tension of the spring can be very accurately adjusted to suit different conditions. The rolls 30 and 35 may be made of rubber and are shown as being secured to sleeves 51 and 50.

The sleeves may in turn be mounted on hubs 52 shown as carried by the shaft 351. The various members may be secured together in any desired manner.

The roller 35 is shown as carrying a plate 53 having thereon a spring pressed pawl member 450 which may engage a ratchet 44 shown as carried on the shaft 351. The coil spring 54 is indicated as carried on said shaft and may be secured at one end to the

ratchet 44 and at the other end to the bearing block 36.

If a strip of paper be led between the two rolls the latter will be rotated thereby winding up the spring 54. After a time the frictional resistance between the paper and the upper roll will be insufficient to overcome the turning tendency produced by the spring which has been wound up and when this occurs the roll will cease to rotate and will merely be held in stationary position even if the paper continues to be pulled out. The amount of turning tendency or the torque exerted by the spring 54 before the paper slips thru the rolls without turning depends on the pressure of the upper rolls upon the paper and this pressure may be governed and adjusted as stated by means of the thumb screw 43.

In the printing of tags, and particularly price tags such as shown at 80 Fig. 9 which are provided with blank spaces to be filled in, it is desirable that the proper portion of the tag be presented to the type or printing surface, these tags usually are in strip form having edges of the strip intermediate, each separate tag notched as at 81 to provide a V-shaped cut which facilitates the separation of the tags from one another. The part of the invention to be now described is particularly adapted for use in connection with the notched tags just described. Plates 60 are shown as adjustably secured to the base 42 and may be provided with upturned portions 61 which act as guides for the strip of paper or tags after they pass between the rollers 30 and 35. Notches 62 are indicated as provided in the plates 60 and in their upturned portions 61. The levers 65 are shown as bent at the end 63 and they may be pivoted at 66 to a bracket member 67, shown as secured to the plate 42.

To adapt the mechanism to control tickets of various widths, I have provided elongated openings 672 in the base of the bearing block 67, thus permitting lateral adjustment of the levers 65. The guide plates 60 likewise have similar openings 602 which permit them to be adjusted laterally with relation to the levers 65.

Suitable springs 68 may be provided to urge the levers to the position shown in Fig. 1. In the assembled machine the notched portion of the plate 60 may be adjustably arranged at a pre-determined distance from the type when the latter are in printing position to thereby align the position of the impression on the tag with the proper blank spaces. To attain this adjustment I have provided elongated openings 422 in the plate 42 and clamp screws 421 which are adapted to adjustably secure the mechanism at any distance from the multigraph within the limits of the slot 422, whereby the mechanism may not only be adjusted for accurate

alignment of the tag but may also be used to adjust the mechanism to control any reasonable length of card. The plate 42 may be provided with an aperture 43 made by slitting the material and bending it down on lines 431 to provide two guides 48 thru which the material may pass to the rolls 30 and 35. The rib 26 is of sufficient length not only to cause the rolls 18 and 19 to advance the paper a distance equal to the width of the ticket but also to advance the strip of tickets a small additional amount so that a notched portion of the ticket passes beyond the bent portion 63 of the levers. It is evident that for handling various lengths of tickets ribs of different length will be required.

As soon as the rib 26 ceases to engage the roller 25 a spring (not shown) moves the bell crank lever upward from the position shown in Fig. 2 until the roller 25 engages the periphery of the drum. In this position the roller 19 is free of contact with the roller 18 and there is now no force tending to advance the strip of paper forward. In advancing the strip however, the spring 54 has been put under tension and is now free to act, rotating the roll 35 and tending to pull the strip of tickets in a direction reverse to that effected by the rolls 30 and 35. This movement will be limited, however, by the lever 65 as soon as the retrograde movement of the tickets brings the notches 81 opposite the bent portion 63 of said lever. All movement of the strip is now stopped and since the notches are accurately centered with regard to the printing surfaces a ticket is in position to be printed.

In the operation of the device each revolution of the drum causes the rib 26 to depress the roller 19, pressing the paper or ticket onto the roller 18 whereby the paper or ticket is advanced. Assuming that before starting the machine the notches 81 in a ticket engage the bent portions 63 of the lever 65, then the rib 26 is proportioned to cause the paper to move forward a distance somewhat greater than the distance between notches. As soon as the roller 19 moves away from the paper forward movement of the latter ceases and at once the spring 54, which has been placed under greater tension by the paper passing between the rollers 30 and 35 and rotating them, causes the paper to be moved backward until the bent portions 63 of the lever 65 spring into engagement with the notches 81 in the paper to thereby arrest movement of the latter. The drum continues to rotate during this positioning movement and when the proper alignment is effected, the printing is done and the operation completed.

It will be noted that uniformity of feed for the strips is secured and also that any irregularity in the distance between notches

will in no manner affect the machine, the combined forward and backward movement eliminating all trouble. The spring 54 may be initially put under tension by manually turning the roller 35 the desired amount.

Having thus described my invention, I claim:

1. The combination with a printing machine of a paper feed device, a paper retracting mechanism, a guide member, and means co-operating with said guide member and adapted to engage the edge of the paper to align certain portions of the paper with a printing surface.

2. The combination, with an impression member and a cooperating platen, of a feeding and aligning device for paper, including two pairs of cooperating positioning rolls, means to render each pair of rolls operative alternately to move the paper in different directions, and a stop adapted to limit the movement in one direction without limiting it in the other direction.

3. The combination with a printing machine, of means to move a strip of paper to printing position, said means comprising a plate member, a roller rotatably carried by said plate member a second freely rotatable roller carried by said plate in contact with said first mentioned roller, means tending to rotate one of the rolls to withdraw the paper to printing position and means for limiting the withdrawing movement.

4. In a printing machine means for aligning notched paper to a printing surface, said means comprising a plate member, a roller rotatably carried by said plate, a second roller, freely rotatable, carried by said plate in contact with said first mentioned rollers, means to regulate the pressure of one roller upon another, means normally tending to rotate one of the rolls to withdraw the paper to printing position and means to limit the withdrawing movement.

5. In a strip feeding device two co-operating sets of mechanisms, one set acting to advance the strip and the other set acting to withdraw it to printing position, said second mechanism comprising a plate member, a roller rotatably supported on said plate, a second roller rotatably mounted adjacent said first mentioned roller, means urging said rollers together, means to rotate one of said rollers, said means tending in operation to withdraw the paper to printing position, and means to limit the withdrawing movement.

6. The combination with a printing machine, means to advance the paper beyond printing position, and means to withdraw the paper to printing position, said second means comprising a plate member, a roller rotatably supported on said plate member, a second roller mounted adjacent said first

mentioned roller, means urging said rollers together, and means tending to rotate one of said rollers and serving in operation to withdraw the paper to printing position, 5 and means to limit the withdrawing movement.

7. In a printing machine, means for aligning notched paper with a printing surface, said means comprising a guide member having a notch therein, a lever co-operating with said notch in said guide member whereby said lever may align the notched portion of said strip with said guide notch.

15. 8. In a strip feeding device, two co-operating sets of mechanisms, one set acting to advance the strip and the other set acting to withdraw it to printing position, said second mechanism comprising a plate member, a roller rotatably supported on said plate, a second roller rotatably mounted adjacent said first mentioned roller, spring means urging said rollers together, a ratchet secured to said upper roller, a pawl therefor, 20 a spring connected to said pawl and to the supporting means for said first mentioned roller, said spring tending in operative position to withdraw the paper to printing position, a pair of levers carried 25 by said plate, a notched guide member carried by said plate, and means for urging said levers into said notches.

9. The combination of a printing drum, an impression-platen, a pair of rollers for 30 advancing the paper, arms for holding one of said rollers out of contact with the other, a roller carried by one of said arms, a member carried by said drum and adapted to engage said last mentioned roller to 35 govern engagement of the feed rollers, means for driving one of the feed rollers, and means for withdrawing the paper to printing position.

10. In a strip feeding device, two co-operating sets of mechanisms, one set acting to advance the strip and the other set acting to withdraw it to printing position, said second mechanism comprising a plate member, a pair of spring members carried by 45 said plate, a roller rotatably carried by said springs, a second freely rotatable roller carried by said plate in contact with said first mentioned roller, means tending to rotate one of the rolls to withdraw the paper 50 to printing position, a pair of pivoted levers carried by said plate, a bent portion near the end of said levers, a notched guide member carried by said plate and springs for urging said bent portions of the levers 55 into said notches.

11. In a strip feeding device two co-operating sets of mechanisms, one set acting to advance the strip and the other set acting to withdraw it to printing position, said 60 second mechanism comprising a plate

member, a pair of bearing members carried by said plate, a roller rotatably carried by said pair of members, a second roller rotatably carried by said plate in contact with said first mentioned rollers, means to 70 regulate the pressure of one roller upon another, means normally tending to rotate one of the rolls to withdraw the paper to printing position and means to limit the withdrawing movement.

12. In a strip feeding device two co-operating sets of mechanisms, one set acting to advance the strip and the other set acting to withdraw it to printing position, said second mechanism comprising a plate member, a pair of blocks removably secured to said plate member, a spring member carried by each of said blocks, a bearing block on each spring, an axle journaled in said bearing block and a roller rotatably carried by said axle, a third pair of blocks carried by the plate, a freely rotatable roller carried by said third block in contact with said first mentioned roller, said springs urging said rollers together, means to adjust the tension of each of said springs comprising a thumb screw, a ratchet secured to said upper roller, a pawl therefor, a coil spring on said axle, one end of said spring being secured to said pawl and the other to said second mentioned blocks, said spring tending in operative position to withdraw the paper to printing position, and means to limit the withdrawing movement.

13. In a strip feeding device two co-operating sets of mechanisms, one set acting to advance the strip and the other set acting to withdraw it to printing position, said second mechanism comprising a plate member, a pair of blocks removably secured to said plate member, a spring member carried by each of said blocks, a bearing block on each spring, an axle journaled in said bearing block and a roller rotatably carried by said axle, a third pair of blocks carried by the plate, a freely second rotatable roller carried by said third block in contact with said first mentioned roller, said springs urging said rollers together, means to adjust the tension of each of said springs comprising a thumb screw, a ratchet secured to said upper roller, a pawl therefor, a coil spring on said axle, one end of said spring being secured to said pawl and the other to second mentioned blocks, said spring tending in operative position to withdraw the paper to printing position, a pair of pivoted levers carried by said plate, a bent portion near the end of said levers, a notched guide member carried by said plate and springs for urging said bent portion of the levers into said notches.

14. In a printing machine means for aligning paper with a printing surface, said means comprising a plate member, a

- pair of blocks secured to said plate member, a spring member carried by each of said blocks, a bearing block on each spring, an axle journaled in said bearing block and a 5 roller rotatably carried by said axle, a freely rotatable roller carried by said plate in contact with said first mentioned roller, said springs urging said rollers together, a ratchet secured to said upper roller, a pawl 10 therefor, a spring on said axle, one end of said spring being secured to said pawl and the other to one of said second mentioned blocks, said last mentioned spring tending to withdraw the paper to printing position, and means to limit the withdrawing movement. 15
15. In a printing machine, means for registering paper with a printing surface, said means comprising a plate member, a 20 roller rotatably supported on said plate member, a second roller mounted adjacent said first mentioned roller, means urging said rollers together, means tending to rotate said rollers in the direction to withdraw the paper to printing position, and means to limit the withdrawing movement. 25
16. In a printing machine, the combination with paper feeding mechanism, of a 30 roller rotatably supported, a second roller adjacent said first mentioned roller, means tending to rotate said rollers in a direction to cause them to withdraw the paper to printing position, and means to limit the withdrawing movement. 35
17. The combination with a rotary printing machine, of means for over feeding the paper, means for retracting the fed paper to printing position, and means for stopping the retracted paper in printing 40 position. 45
18. In a machine for feeding a notched strip, the combination of means to advance the strip, a spring barrel bearing on the strip and tending to partially return it, and a finger to engage one of the notches in the strip and limit the return. 50
19. In a mechanism for feeding a notched strip, the combination with mechanism for feeding the strip forwardly, of a pair of 55 retracting rollers, means for rotating said rollers to cause them to move the paper in a rearward direction, and a pair of fingers adapted to engage notches in the strip during such rearward movement. 60
20. A combination with a printing roll and a platen adapted to print on a strip, of a pair of feeding rollers adapted to draw a strip forward, a second pair of rollers spring actuated and adapted to draw the strip backward, and a pair of spring fingers adapted to engage the opposite edges of the strip. 65
21. The combination with a rotary printing machine, of means to feed paper forward to the machine, a spring operated de- 70 vice for drawing the paper back a portion of the distance fed, and a stopping finger for limiting the backward movement. 75
22. In a strip feeding mechanism, the combination of means for advancing the strip, means for returning the strip a less distance than the advance, and means adjustable for different widths of strip adapted to engage the strip edge to positively limit the return movement. 80
23. In a strip feeding mechanism, the combination of means for advancing the strip, a spring device adapted to partially return the strip, and an adjustable stopping device for limiting the return movement adapted to engage the edges of the strip. 85
24. In a mechanism for feeding a notched strip, the combination of means to advance the strip, a device to partially return the strip, a laterally adjustable guide for the strip, and a laterally adjustable finger adapted to enter one of the notches to limit the return. 90
25. In a machine for feeding a notched strip, the combination of means to advance the strip, a spring device tending to partially return the strip, laterally adjustable edge guides for the strip, and a pair of fingers adapted to engage the notches in the strip and limit the return. 95
26. In a device for feeding a strip notched at its edges, the combination of means for engaging the strip and feeding it forward, means for partially returning the strip, a pair of spring pressed fingers bearing against the edges of the strip and adapted to enter the notches to definitely position the strip, and an adjustably mounted frame adapted to vary the position of all of the mechanism mentioned with reference to a printing machine. 100
27. In a mechanism for feeding a notched strip, the combination with mechanism for feeding the strip forwardly, of a pair of retracting rollers, spring means for rotating them in a rearward direction, a pair of fingers adapted to engage notches in the strip on such rearward movement, and a longitudinally slotted plate carrying the retracting rollers, their spring means and the retarding fingers. 110
28. The combination with a printing machine, of a plate member mounted thereon, a roller rotatably supported on said plate member, a second roller mounted adjacent said first mentioned roller, means urging said rollers together, means tending to rotate said rollers in the direction to withdraw the paper to printing position, and means to limit the withdrawing movement. 120
29. The combination with a printing machine, of a plate member adjustably mounted thereon, a roller rotatably supported on said plate member, a second roller mounted adjacent said first mentioned roller, means 125

- 6
- urging said rollers together, means tending to rotate said rollers in the direction to withdraw the paper to printing position, laterally adjustable edge guides for the paper, and a pair of laterally adjustable spring pressed fingers adapted to engage the edges of the paper adjacent to the edge guides.
30. The combination with a pair of feed rollers adapted to draw a strip of paper forwardly, of a second pair of rollers, spring actuated, adapted to draw the strip rearwardly, edge guides for the strip, and a pair of spring fingers adapted to engage the opposite edges of the strip adjacent to the edge guides.
31. The combination with a rotary printing machine, having a paper feed device, of a spring device for drawing back the material fed, an edge guide for such material and a stopping finger for engaging the strip adjacent the guide to limit the retraction.
- In testimony whereof, I hereunto affix my signature.

HARRY C. GAMMETER.
